UNITED STATES PATENT OFFICE.

ARTHUR F. POIRIER, OF WILTON, MAINE.

BEARING PROTECTOR.

Application filed March 15, 1926. Serial No. 94,888.

This application is devoted to an improvement over the construction shown by my prior U. S. Patent, No. 1,205,012, of November 14, 1916. In the patented structure, 5 a protector was provided for a U-shaped bearing or puppet of a carding machine, said protector consisting of a casing to fit over the upper end of the bearing and having end plates with openings for the reception 10 of the shaft. It was found in actual practice, that when repeatedly removing the casing from the bearing or puppet, whenever it was necessary to disengage the shaft therefrom, the casing would become badly bent 15 and could only be reapplied with difficulty. Moreover, as the puppet heads or bearings in common use are not provided with shaft-receiving channels of uniform depth and 20 are themselves of different sizes, it was impossible to produce a protector which would be universally adaptable to all machines and would not interfere with proper movement of the shaft entirely to the bottom of the shaft-receiving channel. It is to overcome 25 these difficulties that I have produced the novel subject matter hereinafter described and claimed, the description being supplemented by the accompanying drawings.

Fig. 1 is a side elevation of one of the 30 bearings or puppet heads, the shaft mounted therein, and the improved protector operatively related with the bearing and shaft.

Fig. 2 is a transverse sectional view on line 2—2 of Fig. 1.

Fig. 3 is a longitudinal section as indicated by line 3—3 of Fig. 2.

Fig. 4 is a transverse sectional view on line 4—4 of Fig. 1.

Fig. 5 is a side elevation partly broken 40 away and in section, of the protector separate from the bearing and shaft.

Fig. 6 is a transverse sectional view on line 6—6 of Fig. 5.

The numeral 7 on the drawing, designates 45 a conventional form of bearing or puppet head, having the usual shaft-receiving channel 8, and the numeral 9 has reference to the shaft of a working or stripping roller of a carding machine, said shaft engaging 50 the usual bushing 10 in the bottom of the channel 8.

The improved protector comprises a horizontally elongated block 11 of a length and width corresponding to the length and width 55 of the channel 8, and provided with flat sides 12 to contact slidably with the opposed

side walls of said channel. Integral with the ends of this block 11, and projecting downwardly therefrom, are two end plates 13 to contact with the ends of the puppet 60 head or bearing 7, said end plates having openings 14 to receive the shaft 9. By this construction and arrangement, the block 11 will follow the shaft 9 as the latter is inserted into the channel 8, regardless of the 65 depth of this channel, and the device possesses no parts to transversely straddle the puppet head or bearing to interfere with this following motion, regardless of the 70 transverse dimension of said head or bearing. Moreover, the improved protector is readily removable bodily with the shaft 9, without causing any delay or inconvenience whatever.

As in the patent above referred to, col- 75 lars 15 are preferably secured to the shaft 9 to hold the protector against axial movement thereon when said shaft is removed from the bearing.

Preferably, the lower or inner side of the 80 block 11 is longitudinally channeled as at 16 and an oil inlet 17 is formed through said block to the channel. Thus, lubricating oil in abundant quantity may be supplied to 85 the shaft and the bearing.

It will be seen that while the invention is exceptionally simple and inexpensive, it is unusually desirable and will be very efficient to exclude all foreign matter, such as threads, lint and the like from the bearing. 90 On account of the excellent results obtainable from the details disclosed, they are preferably followed. However, within the scope of the invention as claimed, variations may be made.

I claim:—

1. In combination with a bearing having a shaft receiving channel and a shaft engaging the inner end of the channel, a block having a length and width corresponding to the length and width of said channel and provided with flat sides to contact slidably with the outer portions of the opposed side walls of the channel, said block entirely closing the outer portion of the latter and having its inner surface spaced from the shaft, and end plates formed integral with and projecting laterally from the ends of the block and engaging the ends of the bearing to entirely close the ends of the channel, 105 said end plates having openings through 110 which the shaft passes.

2. A protector for a bearing having a shaft receiving channel, said protector comprising a solid substantially rectangular block adapted to be inserted into the channel of said bearing and having flat parallel sides and a longitudinally channelled inner surface and end plates formed integral with

and projecting laterally at right angles from the end of the solid block, said end plates having shaft receiving openings. 10

In testimony whereof I have hereunto affixed my signature.

ARTHUR F. POIRIER.
